UNITED STATES PATENT OFFICE.

LESLIE S. HACKNEY, OF ST. PAUL, MINNESOTA.

PEDAL ATTACHMENT FOR ACCELERATING-LEVERS.

1,214,627.

Specification of Letters Patent. Patented Jan. 30, 1917.

Application filed May 22, 1916. Serial No. 99,043.

To all whom it may concern:

Be it known that I, LESLIE S. HACKNEY, a citizen of the United States, residing at St. Paul, in the county of Ramsey and State 5 of Minnesota, have invented new and useful Improvements in Pedal Attachments for Accelerating-Levers, of which the following is a specification.

My invention relates to improvements in 10 pedal attachments for accelerating levers.

In automobiles and elsewhere, foot levers are usually provided to control the operation of motive-power. In using these levers, the driver places the sole of his shoe against 15 a lever and, in operating said lever, tiltably supports his foot at the heel upon the foot board. This practice has two disadvantages, both of which impair uniformity of control. First, in attempting to hold his foot in the 20 unnatural position described, the driver is fatigued and frequently inefficiently operates the pedal, especially when the vibration of the car is great, and secondly, owing to the frictional contact of the driver's shoe with 25 the foot lever, difficulty is experienced in attempting to uniformly actuate the lever.

The object of my present invention is to 30 obviate these disadvantages and, generally, to provide a simple attachment for the ordinary accelerator levers having a support upon which a driver's foot may freely rest in a natural position and also to provide foot-operated means adapted to coöperate with a pedal, whereby tilting movements of 35 the foot efficiently and uniformly actuate said lever.

Other novel features of construction and 40 combinations of parts will be more fully hereinafter described and pointed out in my claims.

In the drawings, Figure 1 is a perspective view of my improved device, showing the foot board of an automobile upon which said device is mounted and also illustrating an 45 ordinary accelerator lever which is operated by said device; Fig. 2 is a longitudinal central sectional view of my attachment; Fig. 3 is a sectional view taken on the line 3—3 of Fig. 2.

Referring to the drawings, I have used 50 the reference letter A to indicate the pedal and B the standard upon which said pedal is mounted. Said pedal A comprises a spool-shaped foot rest 9 consisting of a hollow 55 cylindrical body 10 having ends 11 enlarged to form annular keepers 12, and an exten-

sion 13 widened at its end to form a sole-contact 14.

The standard B includes a flange 15 adapted to be secured by screws 16 or the like upon the foot board 17 and a post 18 rising from said flange 15 and supplied with a pair of oppositely extending arms 19 turned upward at their ends. These arms 19 have alined perforations 20 therein and 35 are inserted in an opening 21 at the bottom of the foot rest, which is formed by cutting away a portion of the cylindrical body 10. A pintle 22, axially secured in the ends 11 of the foot rest 9, passes through the perforations 20 in the arms 19 and pivotally secures the pedal A upon the standard B. The upturned portions of the arms 19 fit snugly within the ends 11 of the foot rest and prevent sidewise movement of the pedal 75 A, while the opening 21 in the body 10 permits a substantial tilting movement of said pedal without interference with the standard B.

Beneath the sole-piece 14 of the pedal A 80 are two pendant ears 23 in which a roller 24 is revolvably mounted by means of a pintle 25 passing through said roller and ears. My attachment is so positioned upon the foot board 17 that the roller 24 rests upon the accelerator lever 26, as shown in Fig. 1. I employ a pad 27 of rubber, or other suitable frictional material, upon the sole-contact 85 14 of the foot lever. My attachment is easily applied to an automobile by simply 90 securing the flange 15 upon the foot board thereof.

In use, the driver places his foot upon the foot rest 9, as illustrated in dotted lines in Fig. 2, the shank of his shoe resting upon 95 the cylindrical body 10, between the keepers 12 at the ends thereof. It will be readily seen that in such position the foot is freely and naturally supported. The sole of the driver's shoe extends over the sole-piece 14, 100 which may be depressed by tilting the foot. In depressing the pedal, the roller 24 bears upon the lever 26 and, owing to its rolling contact with said lever, causes the same to move uniformly with respect to the movement of the pedal. The usual resilient devices (not shown) which raise the lever 26, necessarily elevate the lever A when pressure is removed therefrom.

This device is particularly advantageous 110 in that it lessens the strain upon the driver of an automobile and, owing to the evenness

of control, promotes comfort in travel and avoids unnecessary wear and tear upon the machine.

Having described my invention, what I claim as new and desire to protect by Letters Patent, is:

1. In a device of the class described, the combination with a foot lever, of a pedal comprising a cylindrical foot rest having 10 keepers at its ends and designed to receive the shank of a shoe and an oscillatory sole-piece integral with said foot rest, a standard upon which said foot rest is axially pivoted and a roller mounted beneath said sole-piece 15 adapted to rest freely in contact with said foot lever.
2. In a device of the class described, the combination with a foot lever, of a standard, a pedal comprising a foot rest designed 20 to receive the shank of a shoe, and an oscillatory sole-piece integral with said foot rest, a pivot securing said foot rest upon said standard, said foot rest being designed so that the pressure thereon is transmitted radially to 25 the pivot in said standard and a roller beneath the sole piece arranged to rest freely in contact with the lever and transmit motion from said pedal to said lever.

3. In a device of the class described, the combination with a foot lever, of a standard, a 30 pedal comprising a hollow cylindrical foot rest having a portion of its annular wall cut away to receive the end of said standard, a pivot passing through said standard and axially arranged within said foot rest, and a 35 sole-piece integral with said foot rest adapted to co-act with said foot lever.

4. In a device of the class described, the combination with a foot lever, of a standard having laterally extended arms turned upward at their ends, a pedal comprising a hollow cylindrical body having ends enlarged to form keepers at the extremities thereof, said body being cut away to receive the arms, the upturned ends thereof fitting snugly 40 within said ends of said body, a pivot mounted in said ends and passing through said arms, said pivot being axially arranged with respect to the cylindrical body, a sole-piece integral with the body and a roller on 45 said sole-piece arranged in rolling contact with said foot lever.

Whereof, I have hereunto subscribed my name to this specification.

LESLIE S. HACKNEY.
